UNITED STATES PATENT OFFICE.

STEPHEN B. ELKINS, JR., OF NEW YORK, N. Y.

METALLIC RAILWAY-TIE.

1,079,936.

Specification of Letters Patent.

Patented Dec. 2, 1913.

Application filed February 9, 1912. Serial No. 676,633.

To all whom it may concern:

Be it known that I, STEPHEN B. ELKINS, Jr., a citizen of the United States, residing in the city, county, and State of New York, have invented a new and useful Improvement in Metallic Railway-Ties, of which the following is a specification.

My invention consists of an improved construction of metallic railway tie, whereby 10 I am enabled to manufacture a more substantial tie than the wooden ties commonly in use, provision being made in the ties constructed under my invention for preventing the spreading of the rails, and also 15 for combining suitable rigidity and sufficient elasticity with a strong and durable construction.

To the above ends, my invention consists in a novel construction of metallic railway 20 tie, which is preferably made in one piece and which is bent in order that the portion of the tie on which the rails rest will be suitably supported.

It further consists of novel details of construction, all as will be hereinafter fully set forth and particularly pointed out in the 25 claims.

Figure 1 represents a perspective view of a metallic railway tie, embodying my invention. Figs. 2 and 6 represent perspective 30 views of metallic railway ties, showing different applications of my invention. Fig. 3 represents a partial perspective view of a portion of the tie shown in Fig. 2, having a flange applied thereto. Fig. 4 represents a 35 perspective view of the fastening means which may be employed, showing the attaching means in proper position. Fig. 5 represents an elevation of the parts seen in 40 Fig. 4, in proper position. Fig. 7 represents a sectional view of a tie showing a different application of my invention.

Similar numerals of reference indicate corresponding parts in the figures.

Referring to the drawings:—My improved railway tie consists essentially of a plurality of connected tubular members, said tubular members extending laterally relative to the tie, and in the accompanying 45 drawings I have shown several embodiments thereof, wherein 1 designates the tie as a whole, 2 the tubular members, the openings of which extend laterally relative to the tie itself or longitudinally with respect 50 to the rails, and 3 designates the connec-

tion between the tubular members serving to prevent improper separation or movement thereof.

In Fig. 1, I have shown the tubular members at the ends of the connecting piece 3, 60 and have also shown a bolt 4 which may be used if necessary, and which is adapted to prevent spreading of the ends of the tubular members.

In Fig. 2 I have shown a construction, 65 wherein a reduced portion 13 of the free end 6 of the metal, forming the tubular members, projects through one side thereof, which thus prevents improper movement or spreading of the tubular members and also 70 can be employed to act as a portion of the fastening for the rail.

In Fig. 3 I have shown a portion of the construction shown in Fig. 2 with a flange 75 applied thereto.

In Figs. 4 and 5 I have shown a construction for securing means for the rails, which consists of a plate 7 having the up-turned ends 8 thereon, and the threaded portions 9 secured thereto, which are adapted to project through suitable openings 10 in the tie, and to receive the nut 11 which when suitably screwed, is adapted to hold the rail in position. In some cases I may employ a washer 12 to assist in holding the rail. 85

In Fig. 6 I have shown a construction in which the free ends 14 of the tubular members contacting with the connecting bar 15 at substantially the point at which the rails are supported, and in Fig. 7 I show a construction similar to that in Fig. 2, the free ends 16 of the tubular members projecting into slots or openings 17 in the connecting bar 18 for evident purposes. 90

From the above it will be understood that 95 my invention broadly consists of a plurality of tubular members suitably connected, having the openings thereof extending laterally with respect to the ties, or longitudinally 100 with respect to the rails, and I desire to use the tie rod or flange or other suitable means that may be necessary in order to make a construction suitable to various conditions encountered, and I do not therefore desire to be limited in every instance to the exact 105 construction herein shown and described.

Having thus described my invention, what I claim as new and desire to secure by Letters Patent, is:—

1. A metallic railway tie, comprising a 110

plurality of connected tubular members formed of a single strip of material, the openings of said members extending laterally relative to the tie, the edges of said members being provided with inwardly extending flanges and means for locking the ends of the metal forming the members with the connection between said members.

2. In a metallic railway tie, a top and end portions, the free ends of which are adapted to pass through the top portion and engage with the rail.

3. In a metallic railway tie, a top and end portions having free ends, which are reduced forming shoulders, said reduced ends being adapted to project through the top and engage with the rail.

4. A metallic railway tie, comprising a plurality of connected tubular members, the openings of said members extending laterally relative to the tie, said members having inwardly extending flanges.

5. A metallic railway tie, comprising a plurality of connected tubular members, the openings of said members extending laterally relative to the tie, the edges of said

members being provided with inwardly extending flanges.

6. A metallic railway tie, comprising a plurality of connected tubular members, the openings of said members extending laterally relative to the tie, said members and the connection between the arms being inwardly flanged.

7. A metallic railway tie formed of a single strip of material, comprising a plurality of tubular members, the openings of said members extending laterally relative to the tie, a connecting member for holding said tubular members in proper position, and the free ends of said tubular members abutting the connecting member directly beneath the point of load.

8. In a metallic railway tie comprising a top and end portions, the free ends of the latter being adapted to extend into said top, whereby the latter is supported and the ends locked in position.

STEPHEN B. ELKINS, JR.
